UNITED STATES PATENT OFFICE.

LEOPOLD THOMAS AND JOS. THOMAS, OF ALLEGHENY CITY, PENNSYLVANIA.

MATCH-MACHINE.

Specification of Letters Patent No. 12,297, dated January 23, 1855.

To all whom it may concern:

Be it known that we, LEOPOLD THOMAS and JOSEPH THOMAS, of Allegheny City, in the county of Allegheny and State of Pennsylvania, have invented certain new and useful Improvements in Machines for Making Wood Matches; and we do hereby declare that the following is a full, clear, and exact description of the construction and operation of the same, reference being had to the annexed drawings, forming part of this specification, in which—

Figure 1, is a plan of our machine. Fig. 2, is a side view. Fig. 3, is an end view of the front of the machine. Fig. 4 is an end view of the rear of our machine.

Our machine is designed to perform automatically the several operations of cutting out the matches from strips of wood previously cut to the right length; applying the phosphoric composition to one extremity of the matches; and then packing the finished matches in boxes which are closed up by the machine, a certain number of matches being placed in each box.

Machines have been previously constructed which perform some of these operations and yet require much of the work to be done by hand; our machine however only [30] requires to have the blocks of wood to be fed in, and the boxes for the reception of the matches supplied, and then nothing more is required to be done.

We will now proceed to describe in detail [35] the various contrivances used in our machine for the accomplishment of these objects.

In the several figures *a*, *a*, is the framework of our machine, consisting of a horizontal table, supported by legs or end pieces. On this table, near the front end of the machine, is a sliding carriage *b*, which moves horizontally between two guides *c*, *c*. On the top of this carriage are two feed rollers, *d*, *d*, placed with their periphery as far apart as the length of the matches which are to be made by the machine. These feed rollers have rough surfaces, so that they may gradually draw in the block of wood from which the matches are to be cut. Friction rollers or cog wheels *e*, *e*, at the end of the feed rolls *d*, *d*, pressing against or gearing into each other, give the feed rollers the required motion to draw down [45] into the carriage a block of wood placed between them. The reciprocating motion of

the carriage *b*, is communicated by means of a cam *f*, on the fly wheel shaft *g*. The cam working against a friction roller *h*, in the front of the carriage. This cam is 60 double, being of the shape shown by dotted lines in Fig. 2, so that each revolution of the fly wheel shaft *g*, brings the cam *f*, twice in contact with the sliding carriage *b*, and thus causes it to be pushed forward 65 twice for each revolution of the shaft *g*, the backward motion of the sliding carriage is not produced by a spring, but by the bent lever *i*, which has its fulcrum at *k*, the extremity of its long arm lying behind 70 the friction roller *h*, in the carriage *b*, and the extremity of the short arm of the lever *i*, lying within the circle of motion of the points of the cam *f*, is touched by each cam as it passes around immediately after that 75 cam has given the carriage its forward motion, and by depressing the extremity of the short arm of the lever *i*, presses back the long arm, and gives the carriage *b*, its backward motion to be ready for the forward 80 stroke to be given to it by the other cam— or more properly by the other half of the cam *f*. Immediately in front of the carriage *b*, is the cutter *j*, which is made of steel. The face of the cutter resembles a 85 row of cylindrical punches (such as are used for punching holes in leather &c.) set in a frame, each punch having a sharp edge. Immediately in front of this cutter *j* is a block of brass *l*. Through which are 90 bored a series of channels or bores, each bore corresponding with and forming a continuation of the bore in the several punches or cutters. These bores gradually enlarging in diameter force the cutter frame 95 toward the front of the machine, so that the matches when cut by the cutters, may pass easily through their respective channels. The cutter frame and channel block are together not quite so long as the matches, 100 so that when the matches are cut they project about one eighth of an inch beyond the end of the channels.

It will be manifest from the description already given that when a block of wood, 105 cut to the same length as the matches to be made, is placed in the sliding carriage *b*, between the feed rollers *d*, *d*, it will be carried down by those rollers until the edge of the block comes in front of the center frame 110 *j*. The sliding carriage *b*, is then pushed forward by the cam *f*, which forces the end

of the block of wood against the edge of the cutters *j*, and the wood being placed in the machine with its grain running in the same direction as the line of motion of the carriage *b*, the wood is forced through the punches or cutters *j*, each making one match. The carriage *b*, is then withdrawn by the bent lever *i*, and the wood being drawn down by the feed rollers until the edge of the block will again come in contact with the edge of the cutters *j*, the operation of cutting out the matches is repeated, and the matches which were made at the former stroke of the carriage *b*, are pushed by those newly made out of the channels, and are received by the carrier wheel *m*. This wheel is placed at the front of the machine, immediately before the mouth or extremity of the channels *l*, and is designed to receive the matches as they pass from the cutters through the channels, and to supply them with the necessary phosphoric preparation. This wheel *m* is solid, and is nearly, though not quite, as thick as the matches are long. A series of holes are bored through this wheel at uniform distances apart, around the wheel near to its circumference. These holes (which are of such diameter as to receive the matches as they pass from the cutters, and allow them to pass through are bored so that the center of each hole in every series is in line of a radius from the center of the wheel, and so that when any one series of holes is opposite the mouth of the channels passing from the cutters, the holes in the carrier wheel will correspond exactly with the holes in the mouth of the channel block. There may be five, ten, twenty, or even more cutters in a row, in which case the number of holes in each series in the carrier wheel will of course be the same. If desired, two more sets of cutters may be placed, one above the other, instead of having so many in a row, which would unnecessarily increase the diameter of the carrier wheel. The phosphoric preparation is supplied to the matches by aid of the carrier wheel as follows: A roller *n*, the surface of which is supplied with a phosphoric preparation, revolves in front of the holes in the carrier wheel, beneath the point where the matches enter the wheel, the roller being made to revolve by a band *n'* passing over a pulley on the end of the roller and over the fly wheel shaft *g*. In its revolutions the roller deposits small portions of the phosphoric preparation in the holes designed to receive the matches, so that when the matches pass into the carrier wheel, the wheel not being as wide as the matches are long, the end of each match projects beyond the face of the wheel, carrying with it the particle of phosphoric preparation deposited by the roller, which adheres to the end of the match. The matches thus placed in the

carrier wheel *m*, are in their turn forced out by those coming after them, and are deposited on a sliding shelf *o*, which lies close to the outer face of the carrier wheel, just below the level of the mouth of the cutter block. As there is a double cam *f*, on the fly wheel shaft *g*, so that the sliding carriage makes two strokes for every revolution of the shaft, there will be two deposits of matches on the sliding shelf for each revolution of the shaft. As the holes in the wheel are deprived of their phosphoric preparation by the passage through them of the matches, it is necessary that the wheel should pass around, in order that a series of holes supplied with the preparation should present themselves before the mouth of the channels through which the matches will pass from the cutters, and also that the holes already exhausted should pass down to the roller *n*, to be replenished. A gradual and constant motion of the carrier wheel will not answer, as it must remain stationary while the matches are being passed into it. The requisite motion is accomplished by means of a wedge *p*, worked by a connection with the sliding carriage *b*. This wedge works in a slot in an upright strip *q*, which slides up and down at the rear end of the frame of the machine. This upright *q* is jointed at its lower extremity to a finger *r*, which works in the teeth of a ratchet wheel *t*, and is kept in place against the ratchet wheel by the spring *s*. This ratchet wheel *t* is placed at the rear end of the machine on the extremity of the shaft *u*, which carries the carrier wheel, so that each time the upright *q*, is raised by the wedge *p*, the finger *r* turns the ratchet wheel slightly round and with it the carrier wheel, the teeth in the ratchet wheel *t*, being so regulated that each time the ratchet wheel is moved one tooth farther around which is twice for each revolution of the fly wheel shaft *g*, it brings the next series of holes in the carrier wheel to their right place to receive the matches from the cutter frame *j*. Having thus described at length the operation of making the matches it remains to explain the means employed for boxing them. The sliding shelf *o*, terminates in an upright piece *v*, the inner face of which is a semicircular curve. Care must be taken that the end of this upright piece *v*, next to the face of the carrier wheel, does not extend to the whole width of the sliding shelf *o*, as it must be so far from the face of the carrier wheel, as to clear the ends of the matches projecting from the carrier wheel. When this sliding shelf has received a double charge of finished matches, it is drawn away from before the carrier wheel as hereinafter described, being slid horizontally to one side, until the upright *v* comes in contact with a similar upright *v'*, fixed on the table of the frame work of the machine. The face of

the upright v' , which is opposite to the face of the upright v , has also a semicircular curve or groove, so that when the two uprights v and v' , come in contact, they form a 5 hollow cylinder, inclosing the matches made by the machine during one revolution of the flywheel shaft. These are held between the uprights v and v' in a round bunch ready to be placed in their box, or rather to have a 10 box placed over them by the machine.

The boxes in which the matches are to be inclosed are cylindrical and in two pieces, one the box, and the other the lid. These pieces of the boxes are placed in pipes w , 15 w' , one on each side of the upright v' , the corner containing the lids, and the latter the boxes. These pipes w , w' , are made long enough to contain a number of boxes, which are continually supplied to the machine through these pipes w , w' . At the base of each pipe w , w' , is a circular opening opposite to the bundle of matches held between the uprights v , v' . These openings are to receive two plungers x , x' , which pass 25 through the pipes w , w' , respectively, at their base, and pressing against the lid and box in opposite directions, push them over the bundle of matches, and close the box. The plungers x , x' , are actuated by levers y , 30 y' , which are moved forward as hereinafter described, and are caused to recede (when the boxes are filled) by springs s ', s' . When the plungers are drawn back, the sliding shelf o , also passes on to its former place in 35 front of the carrier wheel, and is ready for a repetition of the motion already described, when it has received another charge of matches.

The requisite motion is communicated to 40 the sliding shelf o , and the plungers, in the following manner: At the other end of the fly wheel shaft g , from the fly wheel g' is placed a cam z , which gives the requisite motion to the lever a' , the fulcrum of which 45 is at b' , and the other end is attached to a shoving head c' , which is connected with the end of the sliding shelf o . By means of this cam the sliding shelf o is at the proper moment suddenly drawn back to bring together the uprights v and v' , but the stroke of the cam is not yet exhausted, and the 50 sliding shelf being stopped by the upright v' , is not able to move any further back. The shoving head c' , which works in a 55 groove in the table of the machine, is connected with the end of the sliding shelf by a

bolt d' , which having a spiral spring e' , around it, ordinarily keeps the end of the shoving head c' , in contact with the extremity of the sliding shelf o , with so much force 60 that the motion of the lever drawing the shoving head back, also withdraws the sliding shelf o , without separating its contact with the shoving head. When however the sliding shelf is arrested in its progress by 65 the two uprights v and v' coming in contact, the stroke of the cam not being exhausted, the shoving head is drawn still further back, the spiral spring e' being compressed, and the shoving head c' being drawn away from the 70 end of the sliding shelf. The effect of this independent motion of the shoving head, is to press between and against the head or short arms of the levers y , y' , which causes the extremities of the long arms of these levers to press inward, thus forcing the plungers x , x' , through the pipes w , w' , for the purpose of boxing the matches as before described. So soon as the cam z , causes the lever a' to begin to return, the shoving head 75 is drawn back by the spiral spring e' , and again comes in contact with the end of the sliding shelf, and the springs s ', s' causes the plungers to fly back out of the pipes w , w' . The lever a' then returns the sliding 80 shelf o to its first position before the carrier wheel and is ready for repeated action as before. When the sliding shelf has resumed its position, if the box which has been filled has not fallen off from the machine, it will 85 be pushed off the sliding shelf by the fresh charge of matches passing out of the carrier wheel.

Having thus fully described our improved machine and its construction and operation, 90 what we claim as our invention and desire to secure by Letters Patent is—

1. The use of the sliding carriage with the feed rollers for the purposes hereinbefore described.

2. The combination of sliding shelf, shoving head, levers and plungers for the purpose of packing the finished matches in boxes.

3. The carrier wheel and roller for applying the phosphoric composition to the matches by machinery.

LEOPOLD THOMAS.
JOSEPH THOMAS.
